COIN BANK

Donald F. Earl, Melrose, Mass.

Application November 29, 1930
Serial No. 499,037

8 Claims. (Cl. 232—4)

This invention relates to coin banks for savings, and the aim of the invention is to provide a novel and improved bank having, among others, the advantages hereinafter described and 5 claimed.

In the drawing of one embodiment of my invention illustrated and described herein,

Fig. 1 is a plan with certain parts shown in dotted lines;

10 Fig. 2, a front elevation;

Fig. 3, a bottom view with certain parts shown in dotted lines;

Fig. 4, a partial rear elevation;

15 Fig. 5, a vertical section on the line 5—5, Fig. 1, looking in the direction of the arrow;

Fig. 6, a horizontal section on the line 6—6, Fig. 2, looking down;

20 Fig. 7, a vertical section on the line 7—7, Fig. 1, looking in the direction of the arrow; and

Fig. 8, a plan of the novel coin slot guard plate.

Referring first to Figs. 1, 2, my novel coin bank comprises a hollow casing 1, preferably oval in outline, of suitable material, as sheet metal, with a top 2, and open at its lower edge 3, Figs. 5, 7, to 25 receive a base to be described. In this oval form of casing, coin openings or slots, to be referred to, are so provided that all can be seen and used easily from the front of the bank, contrary to the usual case.

30 This casing is provided at its lower edge 3, Figs. 3, 5, 7, with a base member comprising the inner lock carrying plate 5, the peripheral edge of which is at certain points depressed or offset slightly, to form seats 6 for a reason to be stated

35 presently, the edge, outside of the line of these seats being downwardly turned to form the flange 7. The plate 5, is, in turn, provided with an outer or base plate 8, the peripheral edge 9 of which is turned upward against the flange 7

40 and, at suitable points, Fig. 3, provided with ears 10, which are bent inwardly and downwardly upon the seats 6 to lock the plate 8 thereto, and form the base member with a lock chamber therein.

45 The casing 1, Fig. 6, is divided by a core or coin chamber forming member 11 into a plurality of coin chambers 12, 13, 14, 15, of proper sizes to receive respectively the coins of different denominations, and each is indicated on the outside of the casing from left to right, by slots 50 suitably marked as quarters, dimes, nickels, and half dollars. Each chamber also has a vertical slot 255 opening into it, with computing lines 256 adjacent thereto. The core 11 with the

casing, also provides a space 16 of irregular outline which can be used for bills, if desired.

The core is so fashioned as to size and outline that, assembled with the casing, it forms the closed chambers referred to. The core may be 60 provided with struts 17 which serve to assist in keeping the member in proper lateral position by their contact with the wall of the casing, and thus also reinforce the several chamber walls and the walls of the casing.

65 The top 1, Figs. 1, 7, is depressed at certain points near the center to form seats to receive the turned over ears 18 extended upward from the upper edge of the wall 20 of the chambers 12, 15 of the core, and which ears, Figs. 1, 7, extend 70 through slots 19 in the top 1, and by which the core is secured to the top.

The lower edges of some of the walls 20 of the core, Fig. 7, have downwardly directed flanges 21, Figs. 3, 7, which extend through the plate 5 75 and are provided with horizontal slots 22 which receive bolts 23 of a lock 24, Fig. 3, dotted lines, and which serve to lock the base to the casing, as distinguished from the construction wherein bolts or tongues on the base engage lips on the 80 inner face of the casing, which lips interfere with the free removal of the coins from the chamber by permitting them to slide therefrom as when the core is standing upon or held over the counter. Thus the bank is opened by removing the base 85 from the core and casing, left intact with their contents.

Heretofore coin banks have been assembled with the base and core integral. In such case when the cashier at the bank opened the coin 90 bank by removing the casing from the base, he had left in one hand the base and core and the contents, without sufficient lateral protection for the latter when the cashier tipped the case up in order to pour the contents into the coin hopper 95 or receiver which is used to automatically separate the coins. In such case some of the coins were almost sure to be spilled upon the table or counter to the great delay and inconvenience of the cashier.

When my improved bank is to be opened, it is 100 simply turned upside down in the hand, and the base unlocked and removed from the casing and core, thus leaving the latter with the coins in their chambers intact and surrounded by the casing so that the coins cannot be spilled before being 105 poured into the coin hopper. Or, by a quick motion, the bank may be turned over right side up and placed upon the counter and then lifted, leaving the coins stacked and separated ready to be easily counted. This overcomes a source of 110

considerable trouble and complaint at the present time.

The coin slots 25 for receiving the coins are provided preferably with the tops equi-distant from the top of the casing but varying in width and length to receive coins of different sizes. The slots are also guarded by a novel and improved form of guard to prevent the accidental or intentional withdrawal of coins except by unlocking the bank.

My novel coin and slot guarding means, Figs. 1, 5, 7 and 8, comprises a thin plate of resilient metal, as brass, fashioned in a novel manner. The continuous back or rear edge portion 26, Figs. 5, 8, 15 which seats horizontally against the inside of the top 1 of the casing is substantially flat, and forwardly from it, Figs. 7, 8, as a back bone, extend slot-guard-segment- or bar-carrying ribs or tongues 27.

The forward segmental end 28 of each tongue, Figs. 5, 7, 8, is sufficiently long to substantially correspond with the length of the slot it is to guard, Figs. 1, 8, and the tongue itself, Figs. 5, 7, directed downwardly from the back edge and curved forwardly and upwardly so that in their combined outline, the segments or bars correspond to the outline of the casing. The outer edge 29 of each slot guard segment is turned upwardly and, Figs. 5, 7, 8, provided with one or more, herein one, inwardly directed, yielding finger 30 which normally contacts with the casing top and acts as a yielding stop for the slot guard segment member in its upward travel, under the influence of the inwardly pressed coin. The remaining portion of the upturned edge 29 of the segment is proportioned as to height to constitute a positive stop element to prevent forcing the segment up too far, by the edge striking the top of the casing. To further aid in obtaining the accurate adjustment of the action of the finger 30, I cut the upstanding edge 29 of the segment away a little at each side of the base of the finger 30 forming half round slots 300, Figs. 5, 8, which lengthen, in effect, the finger 30 at its inner end and make it more sensitive to pressure, without extending the finger further inwardly.

Each slot-guard-segment so formed and fashioned depends sufficiently, opposite a coin slot, to block a direct entrance to the bank without springing the segment upwardly, as by the coin when the latter is thrust through the slot, the segment yielding sufficiently to permit the coin to be thrust into the bank. As the coins of any denomination, say dimes, vary in thickness according to the time they have been in circulation, it is desirable to provide a guard with an adjustable stopping action as that of the finger 30, so that it will admit readily a new or an old coin and act equally effectively to prevent the withdrawal of each. The object is attained by the construction described, the finger 30 providing the yielding stopping action to admit coins of varying thickness. The cutaway top edge portion of the core walls as shown in Fig. 7 provides a limiting stop member for the downward movement of the guard, thus preventing one from inserting a knife blade or similar member through the slot and depressing the guard member 28 sufficiently to make it inoperative and permit the extraction of coins through the slot by turning the bank upside down.

The upturned edge 29 of the segment, however, prevents the latter from being forced sufficiently upward by the attempted insertion of a coin or by the weight of the coins, if the bank is turned upside down, or by any knife blade or similar

instrument inserted thereunder, to permit extraction of the coin through the slot; it also, if the bank is turned upside down, positions the coins at an angle adverse to extraction. The edge 29 further, as a positive stop, prevents the finger 30 through the repeated application of undue force, from acquiring an improper set that might impair its proper action. The walls of the core forming the chambers 12 to 15 inclusive are, near the point where they touch each other and before separating to engage the casing wall, see Fig. 5, cut away at the top to leave a horizontal straight edge 288 directly under the segmental ends 28 of the coin slot guarding tongues 27 so that said segmental ends cannot be forced downward beyond the horizontal wall defining the cut-away portion of the core. In other words, this horizontal wall 288 constitutes a stop against downward movement of the core slot guarding members 27, thus positively limiting at certain points both the upward movement by the edge 29 and the downward movement by the wall 288.

The guard edge opposite the two slots for quarters and halves respectively near the opposite ends of the bank, are so long and of such contour that it permits the entrance of coins even at the sharply curved end of the slot without jamming the coin against, and perhaps injuring the guard, which has not been possible heretofore with the types of guards used. The coin guard plate is provided also with two positioning tongues 31 which act, in assembling, to assist in positioning the guard plate by abutting against the curved upright walls 20 of the chambers 12, 15 of the core. The rear wall of the casing is provided with a slot 32, Fig. 4, leading to compartment or chamber 16 for bills. To guide the bills downward, a tongue 310 is provided on the guard plate.

The lock 24, already referred to, comprises, Figs. 5, 7, a sheet metal housing 311 provided with lateral ears 33 at its opposite ends which enter slots 34, dotted lines Fig. 3, in the base 5 and are then turned down against the base and rest in depressed seats therein, not shown. In the housing, Fig. 3, dotted lines, are two bolts 34 at opposite sides respectively of the key barrel 36, which bolts are normally held, by a spring 37, extended through the slots 22 in the flanges 21 of the core extended through the base, referred to above, and thus lock the base to the core and casing.

The bolts 35 are withdrawn from the slots 22 by the action of a suitable key when inserted in the barrel 36 and turned.

My invention is not limited to the particular embodiment thereof described and illustrated.

I claim:

1. A coin bank comprising a casing, a core member secured therein having a main body portion forming with said casing coin compartments and having flanges extending downwardly from said main body portion; the casing provided with coin admission slots, and a base with a lock thereon entirely below said main body portion and operable from the base for securing the same to the core flanges below the coin chambers.

2. A coin bank comprising a casing, a core member secured therein and forming therewith coin compartments; the casing provided with coin admission slots, the bank having coin slot guarding segmental members with upwardly curved edges, and an inwardly directed yielding finger thereon, seated against the casing top and yieldable to admit coins through the slots, and the segment edges blocking the exit through said slots, the core fashioned to provide stops against

downward movement of the coin slot guarding segmental members; and a base with a lock securing it to the core.

- 5 3. A coin bank comprising a casing, a core member secured therein and forming therewith coin compartments; the casing provided with coin admission slots, the bank having coin slot guarding segment members with upwardly curved edges provided with a curved yielding finger adjacent the casing top and yieldingly determining the position of the segmental member relative to the slot, the latter yieldable progressively to admit coins, the curved edges adapted to strike the bank top under certain conditions
- 10 15 and thus stop yielding of the fingers and blocking the exit through said slots, the core fashioned to provide stops against downward movement of coin slot guarding members; and a base with a lock securing it to the core.
- 15 20 4. A coin slot guard for coin banks comprising a rear back bone section with yielding slot guarding tongues extended therefrom forwardly, the tongues carrying cupped segmental end portions with resilient stop fingers inwardly extended therefrom.
- 25 30 5. In a coin bank having coin admission slots, resilient slot guarding members therefor with upwardly extended edges having resilient stop fingers extending inwardly therefrom to admit coins, the adjacent upwardly extended edges acting, with the casing top, as a positive stop

to limit upward movement of the slot guarding members.

6. A coin bank having a casing and a core therein forming coin chambers, coin-receiving slots in the casing leading to the chambers, a base member with a lock operatively engaging the core, and cupped coin slot guarding tongues with a top-engaging positive stop edge portion and a yielding stop member thereon, the stop member effective within certain limits of pressure and the stop portion effective thereafter to prevent deforming of the stop member by the exercise of continued and undue pressure thereon for removal of the coins.
7. In a coin bank, an oval coin slot guarding member with one edge upwardly curved and slit to provide segmental tongues, the latter having also each an inwardly directed curved finger yieldable to the limit set by the contact of the upwardly curved edge of the slot guarding member with the bank top to admit coins.

8. A coin bank comprising a casing, a core member having apertured locking flanges extending downwardly therefrom and a hollow base member having two base plates with a lock therebetween, one base plate apertured to receive the locking flanges of the core, and bolts in the lock constructed and arranged to be thrown by a key to enter the apertures in the flanges of the core.
